UNITED STATES PATENT OFFICE.

DANIEL PURSEL BERNHEIM, OF SOUTHBIDGE, MASSACHUSETTS, ASSIGNOR BY MESNE ASSIGNMENTS, TO BAUSCH AND LOMB OPTICAL COMPANY, OF ROCHESTER, NEW YORK, A CORPORATION OF NEW YORK.

OPHTHALMIC MOUNTING AND METHOD.

Application filed March 13, 1923. Serial No. 624,756.

The present invention relates to ophthalmic mountings, more particularly to mountings of the combination-metal-and-composition type, and to methods of making the same.

The object of the present invention is to provide an improved ophthalmic mounting of the above-described character the non-metallic rim of which, constituted of zylonite, celluloid and the like, shall be secured to a standard metal rim without the aid of additional retaining elements, and without involving the necessity of pressing or otherwise deforming the non-metallic material against the metal.

To the above end, the invention consists of the improved ophthalmic mounting and method of making the same hereinafter described, illustrated in the accompanying drawings, and defined in the appended claims.

In the drawings, Fig. 1 is an elevation of an improved ophthalmic mounting constructed according to the present invention; Fig. 2 is a section of a non-metallic rod out of which the non-metallic rim of the present invention may be constructed; Fig. 3 illustrates a step in the manufacture of the non-metallic rim of the present invention; Figs. 4 and 5 are a side and a fragmentary end elevation, respectively, illustrating a further step in the manufacture; Fig. 6 is a section taken upon the line 6—6 of Fig. 5, looking in the direction of the arrows; Fig. 7 is a section of the completed non-metallic rim constructed according to a preferred embodiment of the present invention; Fig. 8 is an elevation of the same; and Fig. 9 is a section taken upon the line 9—9 of Fig. 1.

The standard inner metal rim 2, as is well known, is of substantially circular cross section, and is provided with an inner lens-receiving groove 4 of narrower width than the cross sectional diameter of the rim, as will be clear from Fig. 9. Resulting from the method of manufacture (not illustrated) of the rim 2, the faces of the groove 4 are usually slightly rounded at their junction 8 with the exterior surface 10 of the rim. The invention is not restricted to use in spectacles, but for illustrative purposes, a spectacle mounting is shown in Fig. 1. The spectacle metal rims 2 are split at 12, end pieces 14 being shown secured to the split

ends of the rims. Temples 15 are received between the end pieces 14 in the customary manner. The usual nose bridge is indicated at 16.

The outer rim 18 of the present invention is constructed of resilient, non-metallic material, like zylonite, and is provided with an annular neck or body portion 21 and annular wings 24 and 25. Between the wings 24 and 25 is formed an inner annular slot 20 within which the metal rim 2 is seated. The wall of the slot 20 is circular in cross section, the exterior surface 10 of the metal rim and the wall of the slot 20 being shaped to conform to each other. The outer portions 38 of the wings 24 and 25 that are situated comparatively far from the neck or body portion 21 are nearer together than the portions of the wings that are located between the neck or body portion 21 and these outer portions 38. The mouth 22 of the slot is therefore narrower than the cross-sectional diameter of the rim. The nearer-together portions 38, on opposite sides of the mouth 22, engage the metal rim 2 to hold the rims against separation. As the non-metallic material of the rim 18 is resilient, the metal rim is held snugly in place. The rims 2 and 18 may be assembled by temporarily resiliently separating the wings at the mouth 22 to temporarily open out the distance between the portions 38. The metal rim is then introduced into the slot 20 by way of the opened-out portions 38 of the wings at the mouth 22. In practice, the metal rim 2 is forced into the slot 20, the resilient wings 24 and 25 yielding momentarily at such time to permit the metal rim to become seated within the slot, and then snapping or springing back into normal position, where they firmly engage and hold the metal rim. The rims can not be accidentally separated because of this resilient engagement, but owing to the round contour of the metal rim 2, intentional separation may be readily effected by pulling upon one or both of the split ends 26 of the zylonite rim in a direction away from the metal rim, as indicated by the arrows, Fig. 1. The wings 24 and 25 will then resiliently slide momentarily over the round exterior surface 10 of the metal rim 2 to permit the unseating of the metal rim.

It is preferred to manufacture the non-metallic rim 18 from non-metallic rods 28,

Fig. 2, though non-metallic tubes, instead of rods, may be employed, if desired. The first step is to reduce the rod to proper diameter. This may be effected in any desired manner, but it is preferred not to impose any longitudinal strain upon the rod during the reducing action, for this would disturb the molecular condition of the non-metallic material, and would induce later shrinking in the direction of the length of the rim. Such shrinking would cause the ends of the non-metallic rim to become separated from the end pieces 14. The reducing action is therefore effected by cutting, grinding or buffing in a circumferential direction. A slot having plane parallel walls 30 is then cut longitudinally of the rod, as shown more particularly in Fig. 3. A slot of this character is very easily cut in the rod. The rod is then coiled upon a mandrel 32, and its ends secured in place upon the mandrel, as shown at 34, in Fig. 5. A permanent set is given to the material of the rod while coiled upon the mandrel. This may be done in any well known manner, as by the use of heat. The coil is next cut along a line parallel to the axis of the mandrel 32, as by means of a saw entering a slot 33 in the mandrel. The coiled rod will thus become converted into a plurality of non-metallic rims, one of which is shown in Fig. 8. This figure shows the rim also notched at a point 36 opposite to the split ends 26, to accommodate the bridge 16. The outer portions 38 of the wings 24 and 25 are now bent inward and set in bent position, as illustrated in Fig. 7, so as to enable them to engage around, and fit tightly against, the rounded faces 8, as is illustrated in Fig. 9. This operation may be effected in any desired manner. If tubes, instead of rods, are used to start with, this last step may not be necessary.

Because the non-metallic material is given a permanent set: first, when coiled on the mandrel; and later, when the portions 38 of the wings have been bent, the non-metallic rim will retain its shape, and hold firmly against the metal rim.

It will be understood that the invention is not limited to the exact structural details herein shown and described, but that modifications may be made therein by persons skilled in the art without departing from its spirit and scope, as defined in the appended claims.

What is claimed is:

1. An ophthalmic mounting having, in combination, a rim of substantially circular cross section, and a split rim having an annular slot within which the first-named rim is seated, the wall of the slot being of substantially circular cross section and shaped to conform to the surface of the first-named rim, the split rim being con-

stituted of resilient material and adapted to yield resiliently during the seating of the first-named rim within the slot and during the separation of the rims, the first named rim having a lens-receiving groove. 70

2. An ophthalmic mounting having, in combination, a split outer non-metallic rim having an annular slot, and an inner metal rim having a lens-receiving groove seated in the slot, the mouth of the slot being narrower than the cross-sectional diameter of the metal rim, and the engaging surfaces of the rims being shaped to permit of the ready separation and reassembling of the rims. 75

3. An ophthalmic mounting having, in combination, a metal rim of substantially circular cross-section, and a rim constituted of resilient, non-metallic material having a slot within which the metal rim is seated, the wall of the slot being of substantially circular cross section and shaped to conform to the exterior surface of the metal rim and the mouth of the slot being narrower than the cross-sectional diameter of the metal rim, a wing of the non-metallic rib being adapted to yield resiliently during the seating of the metal rim within the slot and during the separation of the rims, and one of the rims having a lens-receiving groove. 80 85 90

4. An ophthalmic mounting having, in combination, an inner metal rim of substantially circular cross section having an inner lens-receiving groove, and a split outer rim constituted of resilient, non-metallic material having an inner annular slot within which the metal rim is seated, the wall of the slot being of substantially circular cross-section and shaped to conform to the exterior surface of the metal rim, and the mouth of the slot being narrower than the cross-sectional diameter of the metal rim, a wing of the non-metallic rim being adapted to yield resiliently during the seating of the metal rim within the slot and during the separation of the rims, whereby the non-metallic rim may be separated from the metal rim by pulling upon an end of the non-metallic rim in a direction away from the metal rim. 100 105 110

5. An ophthalmic mounting having, in combination, an inner metal rim of substantially circular cross-section having an inner lens-receiving groove of narrower width than the cross-sectional diameter of the rim, the faces of the groove being rounded at their junction with the exterior surface of the rim, and a split outer rim constituted of resilient, non-metallic material having an inner annular slot within which the metal rim is seated, the wall of the slot being of substantially circular cross section and shaped to conform to the exterior surface of the metal rim and the wings of the non-metallic rim being shaped to engage around, and fit tightly against, the said rounded faces, a wing of the non-metallic rim being 115 120 125 130

- adapted to yield resiliently during the seating of the metal rim within the slot and during the separation of the rims, whereby the non-metallic rim may be separated from the metal rim by pulling upon an end of the non-metallic rim in a direction away from the metal rim. 5
6. An ophthalmic mounting having, in combination, an inner metal rim having a lens-receiving groove, and a split outer rim constituted of resilient, non-metallic material having an inner annular slot within which the metal rim is seated, the wall of the slot being shaped to conform to the exterior surface of the metal rim, and the mouth of the slot being narrower than the cross-sectional diameter of the metal rim, the non-metallic rim being adapted to yield resiliently during the seating of the metal 10 rim within the slot and during the separation of the rims. 15
7. An ophthalmic mounting having, in combination, a rim provided with an inner annular slot the mouth of which is narrower than the maximum width of the slot, and a second rim seated within and shaped to conform to the slot having a lens-receiving groove, the portions of the first-named rim near the mouth being adapted to engage the second rim to hold the rims together, one of the rims being constituted of resilient material and adapted to yield when the second rim is forced into the slot to permit the second rim to become seated within the slot. 20
8. The method of making an ophthalmic mounting that comprises longitudinally slotting a rod constituted of resilient, non-metallic material to produce annular wings on each side of the slot, bending inward the material of the rim near the mouth of the slot, temporarily resiliently separating the portions of the wings near the mouth of the slot, introducing a second rim into the slot by way of the opened-out portions, and permitting the opened-out portions of the wings to spring back into normal position to engage the second rim and hold the rims together. 25
9. The method of making an ophthalmic mounting that comprises longitudinally slotting a rod constituted of resilient, non-metallic material, coiling the rod upon a mandrel, setting the material of the rod while coiled upon the mandrel, cutting the coil along a line parallel to the axis of the mandrel to convert the coiled rod into a plurality of rims, bending inward the material near the mouth of the slot of each rim, setting the bent portions of the rims, and introducing a metal rim in one of the non-metallic rims. 30
10. An ophthalmic mounting constituted of two elements only, one a rim of substantially circular cross section, and the other a split rim having an annular slot extending substantially throughout its length within which the first-named rim is seated, the wall of the slot being of substantially circular cross section and shaped to conform to the surface of the first-named rim, one of the rims being constituted of resilient material and adapted to yield resiliently during the seating of the rim of substantially circular cross section within the annular slot of the slotted rim, whereby the rims are locked together substantially throughout their length. 35
11. An ophthalmic mounting as defined in claim 10 in which the rim of substantially circular cross section is provided with a lens-receiving groove and the non-metallic rim is shaped so as to engage around and fit tightly against rounded faces formed at the junction between the exterior surface of the grooved rim and the groove. 40
12. The method of making an ophthalmic mounting that comprises making a non-metallic member in substantially tubular form with a longitudinally extending slot, coiling the member with the slot interiorly disposed upon a mandrel, setting the material of the member while coiled upon the mandrel, cutting the coiled member to convert it into a plurality of rims, and introducing a metal rim in one of the non-metallic rims. 45
13. The method of making an ophthalmic mounting that comprises making a non-metallic member in substantially tubular form with a longitudinally extending slot, coiling the member with the slot interiorly disposed on a mandrel, supporting the interior walls of the member on the mandrel, and cutting the coiled member to convert it into a plurality of rims. 50
14. The method of making an ophthalmic mounting that comprises making a non-metallic member in substantially tubular form with a longitudinally extending slot, coiling the member with the slot interiorly disposed on a mandrel, supporting the internal walls of the member on the mandrel, setting the material of the member while coiled upon the mandrel, cutting the coiled member to convert it into a plurality of rims, opening a rim out at the slot, and introducing a metal rim into the opened-out rim by way of the slot. 55
15. The method of making an ophthalmic mounting that comprises coiling a non-metallic member substantially tubular in form and having a longitudinally extending slot upon a mandrel, supporting the internal walls of the tube upon the mandrel, and cutting the coiled member to convert it into a plurality of rims. 60

In testimony whereof, I have hereunto subscribed my name this fifth day of March, 1923.

DANIEL PURSEL BERNHEIM.
